(57) **CLAIM**

The ornamental design for an earphone jack cable, as shown and described.

DESCRIPTION

1. Earphone jack cable

1.1 : Perspective

1.2 : Perspective

1.3 : Front

1.4 : Back

1.5 : Left

1.6 : Right

1.7 : Top

1.8 : Bottom

Figures illustrate the earphone jack cable, which is made of metal and synthetic resin; this design relates to a product that enables high-quality sound playback by connecting to electronic devices, such as mobile phones, laptops, and tablet PCs.
